[57] CLAIM

The ornamental design for a hanging modular planter, as shown and described.

DESCRIPTION

FIG. 1 is a bottom perspective view of a hanging modular planter showing my new design, the portions of the chain link being omitted for convenience of illustration; FIG. 2 is a top plan view of the top tier thereof, the bottom tier being omitted for convenience of illustration;

FIG. 3 is a side elevational view of the top tier thereof, the opposite side being identical in appearance;

FIG. 4 is a bottom plan view of the top tier thereof; FIG. 5 is a front elevational of the top tier thereof, the rear being identical in appearance;

FIG. 6 is a side elevational view of a single module of the bottom tier thereof, the opposite side being identical in appearance and the top tier and other modules of the bottom tier being omitted for convenience of illustration; FIG. 7 is a front elevational view of the bottom tier module thereof; the rear being identical in appearance; and,

FIG. 8 is a bottom plan view of the bottom tier module thereof, the top being substantially similar in appearance.

FIG. 1

FIG. 2

FIG. 3

FIG. 4

FIG. 5

FIG. 6

FIG. 7

FIG. 8
